UNITED STATES PATENT OFFICE

JOHN B. HADAWAY, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

METHOD OF OPERATING UPON SHOES

Application filed February 3, 1928. Serial No. 251,670.

My invention relates to methods of operating upon shoes, and particularly upon the heel-ends, as in the attachment of heels to the heel-seats.

In the nailing of heels, it is important that each heel shall be located in a definite relation to the counter-portion of the shoe to which it is to be attached, and that both the heel and shoe be similarly positioned with respect to the nailing mechanism. Another instance of an operation upon heels where their relation to the operating instrumentalities must be fixed is found in breasting. An object of this invention is to establish, without requiring skill on the part of the operator or the making of adjustments, and maintain undisturbed such predetermined relation for all the work operated upon, regardless of the varying thickness of the stock and without the possibility of introducing errors by the distortion, through handling or otherwise, of surfaces by contact with which the position of the work is gaged.

For the attainment of this object, I first assemble portions of a shoe upon a last, produce locating means upon the lasted portions under the guidance of the last, position portions of the shoe as determined by the locating means, and finally perform the desired operations upon the positioned work. The locating means is preferably equidistant from a predetermined point for all sizes of shoes, as from a common breast-line of the heels to be attached. In heel-attaching, it is, I believe, novel to place a lasted upper and sole upon a jack which occupies a predetermined position with relation to nail-inserting mechanism, to place a heel in a like predetermined position, and finally to operate the inserting mechanism to drive attaching nails into the heel and shoe-sole. More specifically, as herein exemplified, in heel-attaching, a sole and upper are brought together upon a last provided with openings, and the sole is perforated under the guidance of the openings, for example, by drilling through them. Then the lasted work is placed upon a jack having projections which pass through the openings. As final steps, the shoe and heel or plural heel-portions, as a base and top lift, are po-

sitioned upon the shoe under the influence of the projections, and these are nailed to the heel-seat of the shoe. By following such a procedure, the relation of the shoe and heel to each other and to the points of insertion of the attaching nails is rendered independent of variations in the material, which might interfere with the accuracy of the operation were the parts positioned by external contact with them of gages or clamps. Moreover, since the upper and sole remain upon the last from the time of producing the locating openings until after the heel has been attached, there is no opportunity for these openings to be shifted from their proper relation to the upper or to each other, either as a result of expansion or contraction from atmospheric changes or by stresses sustained in handling. The demand upon the heelng operator in connection with the positioning of the work-portions is limited to putting the last and heel-portions in place under the guidance of the openings and projections.

The steps of my improved method are illustrated in the accompanying drawings, in which

Fig. 1 shows, in broken side elevation, a lasted shoe ready for the production of the locating openings;

Fig. 2 is a similar view, including a drilling mechanism by which the openings are made; and

Fig. 3 is a broken side elevation of the shoe and heel in place in a heel-attaching machine.

In carrying out my method, there is employed a last A, preferably having a fore-part-portion 10 and a separate heel-portion 12. Upon this last there is assembled, in any convenient manner, an insole I, an upper U and an outsole S, there being shown between the insole and outsole a filler-piece F and a shank-reinforcement R. I have chosen to illustrate S as a short sole, its rear extremity reaching just within the breast line of the heel which is to be attached; but the use of a full-length sole is equally within the scope of my invention.

In the portion 12 of the last is a socket 14, which may be oval in horizontal section, its

transverse dimensions approaching those of the last-portion. That is, the socket is preferably of large transverse area, and the wall surrounding it relatively thin. Extending 5 through the last from the interior of the socket to the thread-surface of the heel-portion, and spaced from each other along the longitudinal axis of the last, are two openings 16, 16, in which are inserted protecting 10 bushings 18, 18. The openings 16 are preferably situated, throughout the entire run of last-sizes, at the same distance from a line which corresponds to the location of the breasts of the heels to be attached, the change 15 in lengths between the sizes taking place rearwardly from the outer opening. The socket is comparatively deep, so that a not very great thickness of metal is left at 20. This reduces the leverage which tends to 20 cause the last to rock laterally under pressure in such operations as heelng. It also, with the considerable lateral dimensions of the socket, gives less weight in the cast-metal heel-portion.

25 With the shoe-portions previously indicated in place upon the last, locating openings 22 are produced in the sole under the guidance of the last-opening 16. In referring to the sole, especially in the claims, it 30 is to be understood that either the insole or the outsole, or both these elements are thereby comprehended. The perforation of the sole may be performed simultaneously for both openings 16 by drills 24 rotatably mounted in a frame 26 and driven by gearing 35 28. The drills are shown as acting in co-operation with a bed 30 formed to support the work.

30 The upper and sole-elements being undisturbed upon the last after the production of the openings 22, the shoe is transferred to the apparatus which is to operate upon it. I have illustrated the die-block 32 of a heelng machine, through openings in which 35 move drivers 34 carried by a reciprocatory plate 36. At the side of the die-block opposite the drivers is a jack 38, by which the work is supported for the attaching operation. This jack is either fixed against 40 transverse movement in a predetermined relation to the die-block-openings, or is movable to such unvarying operating position. Its top 40 is shaped to enter the socket 14 of 45 the last, and has two vertical pins or projections 42, 42 arranged to pass through the openings 16 and 22 when the lasted shoe is jacked. The pins alone may hold the jacked shoe in a definite relation to the nailing mechanism, but, to some extent at least, the 50 fit of the jack-top in the socket retains the last against angular and lateral displacement. After jacking the work, a heel or heel- 55 portions are placed over the heel-seat, positioned with reference to the counter-portion 60 of the shoe and to the nailing mechanism 65

by the pins. In the present instance, a heel-base B and a top lift T are thus located. In the base, there are formed, when it is made and in the desired relation to its periphery, 70 openings 44, 44 passing through the heel-seat and tread-ends and spaced to receive the pins. When thus positioned by the pins, the base is symmetrically related to the counter-portion. Said base is recessed at 46 to receive the rear extremity of the short sole S. 75 Since the locating openings are equally spaced from the common breast-line for all sizes of heels, there will be a correct entrance of the sole-end into the recess, regardless of size. The lift T, which may be of rubber, 80 has molded in it depressions 48, 48, also registering with the pins and, when gaged by them, substantially coinciding at its periphery with that of the base. Clearly, since the 85 openings 22 are made after the upper and sole are assembled upon the last, the dimensions of these elements or their distortion in lasting or otherwise cannot affect said openings, and, as the upper and its sole remain 90 in place upon the last after the locating 95 openings have been made and until the heelng operation has been completed, there can be no change in the openings introducing error into the location of the elements. With the lasted shoe, the base and the top lift all 100 positioned correctly with respect to each other and to the nailing mechanism, and the tread-end of the top lift pressed against the under side of the die-block, the drivers 34 are caused to make their inserting stroke, driving nails N, which have been supplied to the die-block-openings, through the lift, base and heel-seat, clinching them upon the last.

105 The advantages of this invention may be summed up by pointing out that it unfailingly produces a correct location of a heel with reference to other shoe-portions in preparation for an operation upon it and without requiring skill or care upon the part of the operator, regardless of errors in the general form of the various parts of the work, and unaffected by any changes likely to occur in these parts.

110 Having described my invention, what I claim as new and desire to secure by Letters Patent of the United States is:

115 1. The method of operating upon shoes, which consists in assembling portions of a shoe upon a last, producing locating means upon the assembled portions while they are 120 upon the last and under the guidance of said last, positioning the portions of the shoe as determined by the locating means, and performing the desired operation upon the positioned work.

125 2. The method of operating upon shoes, which consists in assembling portions of a shoe upon a last, producing locating means upon the assembled portions while they are 130 upon the last, fixing the last with the as-

sembled shoe-portions in a definite position determined by the locating means, positioning another shoe-portion in a relation determined by said locating means, and performing the desired operation upon the lasted work.

3. The method of operating upon the heel-ends of shoes, which consists in assembling the upper and sole of a shoe upon a last, producing locating means in the sole, under the guidance of the last, positioning of a heel upon the sole as determined by the locating means, and performing the desired operation upon the positioned heel.

15 4. The method of attaching heels to shoes, which consists in assembling the upper and sole of a shoe upon a last, placing the lasted shoe upon a jack which occupies a predetermined position with relation to nail-inserting mechanism, placing a heel in a predetermined position with relation to the inserting mechanism, and operating said mechanism to drive attaching nails into the heel and shoe-sole.

25 5. The method of attaching heels to shoes, which consists in assembling the upper and sole of a shoe upon a last placing the lasted shoe upon a jack which occupies a predetermined position with relation to nail-inserting mechanism said jack being provided with heel-locating means placing a heel under the influence of the locating means and operating the inserting mechanism to attach the heel to the shoe-sole.

35 6. The method of attaching heels to shoes, which consists in assembling the upper and sole of a shoe upon a last, producing openings in the sole while upon the last, placing the last and assembled portions upon a jack having projections arranged to pass through the openings, positioning a heel upon the sole under the influence of the projections, and nailing the heel to the sole.

45 7. The method of attaching heels to shoes, which consists in assembling the upper and sole of a shoe upon a last, producing openings in the sole while upon the last, placing the last and assembled portions upon a jack having projections arranged to pass through the openings, applying successively to the projections a heel-base and a heel-lift in which are openings to receive said projections, and simultaneously nailing the base and lift to the sole.

55 8. The method of operating upon shoes, which consists in assembling portions of a shoe upon a last having openings, producing openings in the assembled portions under the guidance of the last-openings, placing a portion of the shoe in a position determined by the openings, and performing the desired operation upon the work.

65 9. The method of attaching heels to shoes, which consists in assembling a sole and an upper upon a last provided with openings at

the heel-end, perforating the sole through the openings, placing the lasted shoe upon a jack provided with projections which pass through the last-openings and sole-perforations, applying a heel to the projections, and 70 nailing the heel upon the sole.

10. The method of operating upon shoes, which consists in assembling portions of a shoe upon a last, producing locating means upon the assembled portions while they are 75 upon the last, such locating means being equidistant from a predetermined point for all sizes of shoes, positioning the portions of the shoe as determined by the locating means, and performing the desired operation upon 80 the positioned work.

11. The method of attaching heels to shoes, which consists in assembling the upper and sole of a shoe upon a last, producing openings 85 in the sole while upon the last, said openings being equidistant for all sizes of shoes from a breast-line common to all, placing the last and assembled portions upon a jack having projections arranged to pass through the openings, positioning a heel upon the sole 90 under the influence of the projections, and nailing the heel to the sole.

In testimony whereof I have signed my name to this specification.
